(57) CLAIM

The ornamental design for a table, as shown.

DESCRIPTION

FIG. 1 is a perspective view of a table according to my design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a bottom plan view thereof.

The broken lines are for environmental purposes only and form no part of the claimed design.
